UNITED STATES PATENT OFFICE.

FRANK MATTHEW PRESTON, OF VICTORIA, BRITISH COLUMBIA, CANADA.

UNDERWATER CONCRETE BUCKET.

Application filed November 7, 1921. Serial No. 513,589.

To all whom it may concern:

Be it known that I, FRANK MATTHEW PRESTON, a subject of the King of Great Britain, and a resident of the city of Victoria, in the Province of British Columbia, Canada, have invented certain new and useful Improvements in Underwater Concrete Buckets, of which the following is a specification.

10 My invention relates to improvements in underwater concrete buckets, and the object of my invention is to devise a bucket for use in laying concrete under water from which the water may be excluded during the dumping of the concrete batch therefrom, thus enabling the concrete to be laid in place without undue disturbance, since by the exclusion of the water from the space formerly occupied by the concrete, the swirl set up in 15 the buckets in use at the present time due to the inrush of water as the concrete leaves the bucket is entirely eliminated so that much more satisfactory results are obtained.

I attain this object by the construction 25 illustrated in the accompanying drawings in which—

Fig. 1 is a side elevation of the bucket.

Fig. 2 is a part sectional elevation.

Fig. 3 is a view showing an alternative 30 construction of the lower end of the bucket.

The bucket, indicated generally by the numeral 1, is formed as shown in Figs. 1 and 2, although its shape is immaterial. Longitudinally, however, it must be designed 35 so as to be capable of dumping concrete under gravity only, while in horizontal section it may be circular or any other suitable shape.

In the construction illustrated the bucket 40 1 consists of a cylindrical upper end 2 and a cylindrical lower end 3 connected together by a tapering intermediate portion 4. The lower end is of less diameter than the upper end and both ends are closed by watertight doors 5 and 6, the lowermost one of which 6 is capable of being opened by means of a trip line 7 led to a suitable point above the surface of the water.

The length of the lower portion 3 may 45 be varied according to the use the bucket

is put to and may be constructed as shown in Fig. 3, the lower door being then mounted accordingly.

Connected to the upper end of the bucket is an air supply hose 8 the opposite end of 55 which is connected to an air compressor (not shown), this pipe being provided with a suitable safety valve 9, pressure gauge 10, and control valve 11.

The manner in which the device is used 60 and operated may be briefly described. In use the bucket is filled with concrete, indicated by the numeral 12, and the watertight cover 5 closed, air then being turned on until the air pressure in the bucket is sufficient 65 to balance the water pressure at the required depth. The bucket is then lowered to the designated position and the lower door 6 opened by means of the trip line 7 so that the concrete is discharged, the operator meanwhile controlling the air supply 70 by means of the valve 11 to maintain the air pressure in the bucket constant as the concrete leaves it, from which it will be seen that the water is prevented from 75 rushing into the bucket so that there is no undue disturbance of the concrete while laying and thus highly satisfactory results are obtained.

In the alternate construction shown in 80 Fig. 3 the lower end or mouth of the bucket is extended on three sides so that the door may operate in a protected position, the door when opened, as indicated by dotted lines, forming the fourth side of the extension. 85

What I claim as my invention is:—

A device of the character described comprising, an open ended bucket member having an air inlet opening adjacent its upper 90 end and a watertight door for each open end, and a three sided extension on the lower end of the bucket between two sides of which the door swings when opening, the open door forming the fourth side of 95 the extension.

Dated at Victoria, B. C., this 20th day of October, 1921.

FRANK MATTHEW PRESTON.
